DOOR LATCHING MECHANISM

Frederick A. Melzer, Gary, Ind.

Application January 11, 1947, Serial No. 721,631

10 Claims. (Cl. 212—4)

1

This invention relates to latching mechanisms for self-sealing coke oven doors and the like.

Coke oven doors must be tightly sealed in order to assure efficient operation of the ovens. The doors must be easily latched and unlatched preferably automatically since they are removed and replaced by a mechanical head on a peel or ram which withdraws the doors to permit emptying and charging the ovens. Mechanical operators which move the latches only a set amount require constant attention and adjustment to compensate for warpage of the doors and frames. Spring loaded latches may be sufficiently positive in action but they require heavy springs, the sudden release of which results in shocks or jolting which loosens and cracks the brickwork.

It is accordingly an object of this invention to provide a coke oven door latching mechanism which is simple in design and dependable in operation.

It is another object to provide a coke oven door latching mechanism which seals the door tightly without destructive shocks or jolts.

It is a further object to provide a coke oven door latching mechanism which is readily adjustable.

The foregoing and further objects will be apparent from the following specification when read in conjunction with the attached drawings wherein:

Figure 1 is a side elevation, partly in section;

Figure 2 is a side elevation of the hydraulic shock absorber, partially broken away to show the interior thereof;

Figure 3 is an enlarged detail;

Figures 4, 5, and 6 are side elevations, partly in section, illustrating the sequence of movements of the latching mechanism; and

Figure 7 is an enlarged sectional detail of the by-pass 118 of Figure 2.

Referring more particularly to the drawings, the numeral 2 indicates a raising and lowering device for a coke oven door 4 mounted on a reciprocable carriage 6. The raising and lowering device 2 comprises a vertical frame 8 having a vertically disposed screw-threaded spindle 10, journaled therein. The spindle passes through a fixed sleeve nut 12 in a tubular housing 14 so that turning of the spindle 10 by operation of reversible motor 16 and gear reducer 18 raises and lowers the housing 14. Carried by the housing 14 are a pair of hook brackets 20 adapted to be entered into slots 22 in the door 4 and upon elevation of the housing to lift the door 4 and upon withdrawal of the carriage 6 to remove the door from the frame 24.

2

As shown in Figures 1 and 3, a pair of latching bars 26 are disposed in a horizontal plane across the front of the door 4. The bars carry cams 28 intermediate their ends which are adapted to move the rod away from the door when rotated by the latching arm 30 extending outwardly from the cam 28. The ends of the bars 26 are adapted to be disposed in slotted brackets 32 mounted on the door frame. Thus when the arms 30 are moved outwardly away from the door, cams 28 engage cam plates 34 on the door and due to the ends of the arms being held in brackets 32 move the door inwardly against the frame to effect a tight seal.

5 Also mounted on the vertically reciprocable housing are upper and lower buffer wheels 36. These are mounted on rods 40 which may move rearwardly against the resistance of compression springs 42. Rail plates 44 may be provided on the door which are adapted to be engaged by the buffer wheels 36. Disposed below the buffer wheels 36 and carried by the rods 40 are brackets 46 having forwardly opening U-shaped slots 48 adapted to receive the latch bars 26.

10 20 25 Disposed above the buffer wheels and likewise carried by the vertically reciprocable frame 8 are lever arms 50 keyed to shafts 52.

The inner ends of the arms 50 are connected to the piston of a hydraulic shock absorber to 30 be later described and the outer ends comprise generally U-shaped jaws 54. The jaws 54 have inner legs 56 and somewhat shorter outer legs 58.

35 Mounted on the outer ends of the shafts 52 are two tension discs 60 and 62. The outer tension discs 60 are keyed to shafts 52 but the inner discs 62 are rotatably mounted thereon. The discs have opposed shoulders 64 between which there are disposed compression springs 66. One of the shoulders is offset from the plane of the disc so 40 as to oppose directly the other shoulder. Inner discs 62 have stop pins 68 adapted to be engaged by shoulders 70 on the outer discs. The inner discs 60 have shoulders 72 which engage cams 74 on the buffer wheel housings when the carriage is moved towards the door. Thus when the shoulder 72 engages the cam 74, the spring 66 is compressed. This in turn transmits torque 45 through disc 60 and shaft 52 and actuates the lever arm 50 to move the jaw 54 down and lift the inner end upwardly to lift the piston of the shock absorber. It may be noted that movement of the rotatably mounted disc 62 is limited in 50 one direction by engagement of the pin 68 and shoulder 70 and in the other direction by full compression of the spring 66.

55 Upper and lower shock absorbing fluid-actu-

ated pressure releasers designated generally by the numeral 80, are pivotally mounted as at 82 on the vertically reciprocable framework 8. The shock absorbers comprise a housing 84 having a piston 86 in a chamber or cylinder 88. Disposed upwardly along one side of the chamber 88 and underneath thereof is an oil chamber or reservoir 90. The reservoir 90 also extends at least part way up the other side of the cylinder providing a valve chamber 92. Oppositely disposed valves 94 and 96 connect the two chambers and the cylinder. Valve 94 seats interiorly of the cylinder chamber 88 so that lifting the cylinder opens it to permit oil to be drawn into the cylinder. Valve 94 seats on a combined seat and guide member 98 held in place by a retaining ring 100. Valve 96 seats on the outside of the cylinder and opens to permit oil to flow from the cylinder to the reservoir when the pressure of the spring 102 holding the valve closed is exceeded. The adjustment or pressure of the spring is controlled by the nut 104 which is easily adjusted. A lock nut 106 abuts against the frame to keep nut 104 from turning after the desired adjustment is effected. The valves may be replaced by withdrawing nuts 104 and 106, the oil reservoir emptied through drain plug 110 and filled through plug 112.

Grooves 114 and 116 are provided in the walls of cylinder 88 above and below the piston when in its lowermost position. These grooves are connected by a by-pass 118. Thus when the piston has been lifted upwardly and the chamber therebelow filled with oil, the upper groove is covered by the piston so that lowering of the piston is controlled by the valve spring 102. However, as the piston approaches its lowermost position, the upper groove 114 gradually becomes uncovered allowing an increasing amount of oil to pass through the by-pass 118. Thus the pressure within the cylinder is gradually and completely relieved as the piston descends to its lowermost position. A duct 120 connects the upper end of the cylinder 88 and the reservoir 90 so that any oil above the piston will be returned to the reservoir when the piston is lifted. A spring 122 is provided for properly positioning arm 59 and piston 86 of the upper shock absorber.

In operation, assuming that the door is latched in position and it is desired to remove the same, the carriage 6 is moved forwardly until the buffer wheels 36 contact the abutments 44 and the latch bars 26 are received in slots 48, as shown in Figure 4. It is noted in this position, the jaws 54 are held in the proper position respecting latching arms 30. With continued advance of the carriage, buffer springs 42 are compressed allowing jaws 54 to move latching arms 30 forwardly and release cams 28 from cam plates 34. By this time, lifting hooks 20 have advanced through slots 22. This advance causes shoulders 72 to contact cams 74 and, as shown in Figure 5, rotate tension discs 62 and compress the springs 66. This causes the shafts 52 to turn thereby moving the jaws 54 downwardly so that jaw 58 engages the latch arm 30 and at the other end upward movement of the levers 50 lifts the pistons 86 and draws the oil into the chamber 88, as shown in Figure 6. Although, for the sake of clearer illustration, the spring 66 is shown as fully compressed in Figure 5 with jaw 54 in its upper position, and in Figure 6 the shoulder 70 is engaging the stop pin 68 with the jaw moved to its lower position, the movement is actually one continuous combined movement rather than two sep-

arate movements. Motor 16 is now energized to rotate shaft 10 to lift the housing 14 upwardly to cause hooks 20 to engage the door 4 and lift it from its frame 24. The door may now be withdrawn, for ramming the coke, by withdrawing carriage 6. It is noted that the door 4 and the latch bar 26 are securely held by reason of the pressure of springs 42 on the buffer wheels 36 which bear on the rail plates 44.

10 After charging the oven, the carriage 6 is moved forwardly until the door 4 engages the frame 24. The housing 14 is then lowered to free the hooks 20 and enter the latch bar 26 in hooks 32 whereby the door 4 is held on the frame. Upon withdrawal of the carriage 6, the latch arms 30 are pulled outwardly by jaws 54 causing the cams 28 to engage cam plates 34 and thereby seal the door tightly. The extent of the engagement of the jaws 54 and latch arms 30 is controlled by the 15 shock absorbers 89. As the carriage 6 is moved backwardly, the jaw 58 is held in engagement with the arm 30 by the pressure under the piston 86. Release of the arm 30 is adjustably controlled and occurs when the piston 86 has traveled a 20 certain distance. The control is secured by adjusting the spring load on the valve 96 with the nut 104. The valve 96, therefore, holds the oil in the cylinder until a predetermined pressure is reached when it opens and allows the escape 25 of oil. As the oil escapes the piston 86 moves downward. In its downward movement the piston 86 gradually uncovers the groove 114 permitting oil to flow through the bypass 118 around the piston 86 to the opposite end of the cylinder. As 30 groove 114 is uncovered, the pressure is relieved and the spring 92 closes the valve 96. However, the oil flowing freely through the by-pass 118 allows rapid travel of the piston 86 and thus quick 35 release of the arm 30 by the jaw 58 is secured.

40 Due to gravity the piston 86 continues to travel downward and force oil through the by-pass 118 until it reaches the groove 116 which acts as a cushion to slow down and stop the piston 86 without hammer. This puts the jaw 58 in starting position.

45 On the opposite or gripping stroke the oil will flow easily through the by-pass and through the valve 94 to fill the space under the piston as it travels to the opposite end of the cylinder. There will be little back pressure of the piston 86 to resist the movement of the jaw 58, under pressure of the spring 66, in gripping the arm 30.

50 The spring 102 and valve 96 will relieve any shocks which might occur in latching the door 4 to the frame 24.

55 While I have shown and described one specific embodiment of my invention, it will be understood that this embodiment is merely for the purpose of illustration and description and that various 60 other forms may be devised within the scope of my invention, as defined in the appended claims.

I claim:

65 1. A device for operating a latching arm on coke oven doors and the like, said device being mounted on means for lifting doors and comprising a lever pivotally mounted on a shaft, a jaw on said lever adapted to engage said arm, a pair of opposed discs having opposed shoulders, a compression spring between said shoulders, one of said 70 discs being operatively connected to said lever, and means to rotate the other of said discs as said lifting means is advanced toward said door to compress said spring and thereby move the said disc connected to said lever to cause the jaw on said lever to engage said arm.

2. A device for operating a latching arm on coke oven doors and the like, said device being mounted on means for lifting doors and comprising a lever keyed to a rotatable shaft, a jaw on said lever adapted to engage said arm, a pair of opposed tension discs having opposed shoulders mounted on said shaft, one of said discs being keyed to said shaft, a compression spring between said shoulders, and means to rotate the other of said discs as said lifting means is advanced toward said door to compress said spring and thereby move the said keyed disc to cause the jaw on said lever to engage said arm.

3. A device for operating a latching arm on coke oven doors and the like, said device being mounted on means for lifting doors and comprising a lever keyed to a rotatable shaft, a jaw on said lever adapted to engage said arm, a pair of opposed tension discs having opposed shoulders mounted on said shaft, one of said discs being keyed to said shaft, a compression spring between said shoulders, means on said discs to maintain said spring under compression and means to rotate the other of said discs as said lifting means is advanced toward said door to compress said spring and thereby move the said keyed disc to cause the jaw on said lever to engage said arm.

4. A device for operating a latching arm on coke oven doors and the like, said device being mounted on means for lifting doors and comprising a lever keyed to a rotatable shaft, a U-shaped jaw on said lever adapted to engage said arm, a pair of opposed tension discs having opposed shoulders mounted on said shaft, one of said discs being keyed to said shaft, a compression spring between said shoulders, a shoulder on said keyed disc adapted to engage a pin on the other of said discs to maintain said spring under compression, and means to rotate the other of said discs as said lifting means is advanced toward said door to compress said spring and thereby partially rotate said keyed disc to cause the jaw on said lever to engage said arm.

5. A device for operating a latching arm on coke oven doors and the like, said device being mounted on means for lifting doors having spring-biased buffer means engaging the door as the lifting means is moved toward the door and comprising a lever keyed to a rotatable shaft, a U-shaped jaw on said lever adapted to engage said arm, a pair of opposed tension discs having opposed shoulders mounted on said shaft, one of said discs being keyed to said shaft, a compression spring between said shoulders, a shoulder on said keyed disc adapted to engage a pin on the other of said discs to maintain said spring under compression, and means on said buffer means to rotate the other of said discs as said lifting means is advanced toward said door to compress said spring and thereby partially rotate the said keyed disc to cause the jaw on said lever to engage said arm.

6. A device for operating a latching arm on coke oven doors and the like, said device being mounted on means for lifting doors and comprising a lever pivotally mounted on a shaft, a jaw at the outer end of said lever adapted to engage said arm, a fluid-actuated shock-absorbing pressure-responsive release, said release having a piston connected to the inner end of said arm, a pair of opposed discs having opposed shoulders, a spring compressed between said shoulders, one of said discs being operatively connected to said lever, means to rotate the other of said discs as said lifting means is advanced toward said door to compress said spring and thereby move

the said disc connected to said lever to cause the jaw on the end of said lever to engage said arm and lift the piston of the shock absorbing pressure-responsive release to release said jaw from said arm without shock after a predetermined pressure has been exerted on said arm when said lifting means is removed from said door.

7. A device for operating a latching arm on coke oven doors and the like, said device being mounted on means for lifting doors and comprising a lever keyed to a rotatable shaft, a jaw at the outer end of said lever adapted to engage said arm, a fluid-actuated shock-absorbing pressure-responsive release, said release having a piston connected to the inner end of said arm, a pair of opposed tension discs having opposed shoulders mounted on said shaft, one of said discs being keyed to said shaft, a spring compressed between said shoulders, means to rotate the other of said discs as said lifting means is advanced toward said door to compress said spring and thereby move the said keyed disc to cause the jaw on the end of said lever to engage said arm and lift the piston of the shock absorbing pressure-responsive release to release said jaw from said arm without shock after a predetermined pressure has been exerted on said arm when said lifting means is removed from said door.

8. A device for operating a latching arm on coke oven doors and the like, said device being mounted on means for lifting doors and comprising a lever keyed to a rotatable shaft, a jaw at the outer end of said lever adapted to engage said arm, a fluid-actuated shock-absorbing pressure-responsive release, said release having a piston connected to the inner end of said arm, a pair of opposed tension discs having opposed shoulders mounted on said shaft, one of said discs being keyed to said shaft, a spring compressed between said shoulders, means on said discs to maintain said spring under compression, means to rotate the other of said discs as said lifting means is advanced toward said door to compress said spring and thereby move the said keyed disc to cause the jaw on the end of said lever to engage said arm and lift the piston of the shock absorbing pressure-responsive release to release said jaw from said arm without shock after a predetermined pressure has been exerted on said arm when said lifting means is removed from said door.

9. A device for operating a latching arm on coke oven doors and the like, said device being mounted on means for lifting doors and comprising a lever keyed to a rotatable shaft, a U-shaped jaw at the outer end of said lever adapted to engage said arm, a fluid-actuated shock-absorbing pressure-responsive release, said release having a piston connected to the inner end of said arm, a pair of opposed tension discs having opposed shoulders mounted on said shaft, one of said discs being keyed to said shaft, a spring compressed between said shoulders, a shoulder on said keyed disc adapted to engage a pin on the other of said discs to maintain said spring under compression, means to rotate the other of said discs as said lifting means is advanced toward said door to compress said spring and thereby partially rotate said keyed disc to cause the jaw on the end of said lever to engage said arm and lift the piston of the shock absorbing pressure-responsive release to release said jaw from said arm without shock after a predetermined pres-

sure has been exerted on said arm when said lifting means is removed from said door.

10. A device for operating a latching arm on coke oven doors and the like, said device being mounted on means for lifting doors having spring-biased buffer means engaging the door as the lifting means is moved toward the door and comprising a lever keyed to a rotatable shaft, a U-shaped jaw at the outer end of said lever adapted to engage said arm, a fluid-actuated shock-absorbing pressure-responsive release, said release having a piston connected to the inner end of said arm, a pair of opposed tension discs having opposed shoulders mounted on said shaft, one of said discs being keyed to said shaft, a spring compressed between said shoulders, a shoulder on said keyed disc adapted to engage a pin on the other of said discs to maintain said spring under compression, means on said buffer means to rotate the other of said discs as said lifting means is advanced toward said door to

compress said spring and thereby partially rotate the said keyed disc to cause the jaw on the end of said lever to engage said arm and lift the piston of the shock-absorbing pressure-responsive release to release said jaw from said arm without shock after a predetermined pressure has been exerted on said arm when said lifting means is removed from said door.
